SWIMMING POOL WATER LEVEL CONTROL SYSTEM

Donald J. Leslie, Pasadena, Calif.

Application May 6, 1952, Serial No. 286,287

2 Claims. (Cl. 210—11)

This invention relates to a water circulating system for swimming pools or the like, and in which the water of the pool is intended to be cleaned, as by passing it through a filtering tank.

One method of maintaining the water of a swimming pool clean is to skim the surface thereof continuously, since a major portion of foreign material collects at the surface. To this end, a skimming gutter is customarily provided, and a thin film of water is intended to flow over the ledge of the gutter from the main body of water, thence passed through a filtering tank, and back to the main body of water, with the assistance of a water pump.

For proper operation of the pump, the rate that the water flows into the skimming gutter must precisely balance the rate at which the pump can withdraw this water. If such condition can be maintained, the pump continuously has its charge, thereby avoiding an air lock. Furthermore, this balanced relationship is important in order that the level of water in the gutter may be maintained sufficiently below the ledge for the skimming action to take place. This balanced condition is highly dependent upon a precise incremental height of water of the pool as compared with the level of the ledge of the skimming gutter. If the water level is too low, water enters the gutter at a reduced rate and the pump runs dry. If the water level is below the ledge, no cleaning action whatsoever takes place. If the level is too high, the gutter becomes filled since the capacity of the pump has not increased, and soon the level of the gutter is the same as that of the main body of water, and no skimming action or surface flow takes place.

A float valve operated in response to a change in level of the water in the pool could be provided, adding water to the pool from an external source. In such a system, the operating mechanism would have to be set such that a very accurate level would be maintained with respect to the rate at which the pump withdraws the water over the ledge, in order to make best use of the pump. If the rate that the pump withdraws the overflow water be subject to change, such valve mechanism would have to be adjusted accordingly. Furthermore, such adjustment would be extremely critical, since even a few thousandths of an inch added to the water level would have a cumulative effect upon the system.

It is an object of this invention to overcome such disadvantages, and to improve, in general, the circulating systems of this general character.

It is another object of this invention to provide a circulating system for a swimming pool or other body of liquid, utilizing a skimming gutter in which the level of water in the pool is automatically maintained within extremely close limits in relation to the rate that the pump can handle the overflow. By such a system, independent adjustment of a float operated mechanism for different pump installations is obviated, and the system can readily be operated for different circulating rates.

It is another object of this invention to provide a system of this character that maintains a precise level of wa-

2

ter in the pool without requiring expensive extra-sensitive equipment.

It is still another object of this invention to provide an improved system for maintaining a precise level of water in a swimming pool, or other container, utilizing a sump fed by the skimming gutter, and an external water supply operated in response to a decrease in level of water in the sump, thereby maintaining a charge for the circulating pump, and providing an incremental volume of water for the pool as determined by a decreased rate of flow of water into the skimming gutter.

This invention possesses many other advantages, and has other objects which may be made more clearly apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawings:

Figure 1 is a diagrammatic view illustrating a swimming pool incorporating the present invention;

Fig. 2 is a plan view, taken in the direction illustrated by the line 2—2 of Fig. 1;

Fig. 3 is an enlarged view illustrating a portion of the operative mechanism illustrated in Fig. 1;

Figs. 4 and 5 are sectional views, taken along the planes indicated by lines 4—4 and 5—5 of Fig. 3, respectively;

Fig. 6 is a view similar to Fig. 3, illustrating a modified form of the present invention; and

Fig. 7 is a sectional view, taken along the plane indicated by line 7—7 of Fig. 6.

In the drawings, a conventional form of swimming pool 10, formed in this instance of poured concrete, is illustrated. It contains a main body of water 11. At one end of the swimming pool there is provided an outlet 12 of a water supply line 13 for maintaining the desired volume of water 11 in the pool 10. At the other end of the pool 10 is a scum gutter 14 adapted to receive water from the pool 10. It is generally of channel configuration. One side of the gutter 14 is formed by a vertical ledge 15, the upper edge of which cooperates with the upper surface 16 of the body of water 11 to produce a skimming action. The gutter 14 may be formed of poured concrete integrally with the pool, or in any suitable manner.

The gutter 14 is illustrated as extending only along one end of the pool 10, and the supply line 13 is illustrated as disposed at the opposite end of the pool 10. Accordingly, the flow of the upper level of water extends uniformly in one direction substantially throughout the length of the pool. A complete skimming action is thus provided.

Other arrangements could be provided; the specific form herein illustrated serves merely as a basic organization in which the system incorporating this invention is used.

If the surface 16 is slightly above the ledge 15 and the level of water in the gutter is substantially less, a film of water will flow over the ledge, producing the desired skimming action.

This upper film of water may be of the order of several hundredths of an inch in thickness. It will contain a substantial amount of any foreign material that may be in the pool.

Water received by the gutter 14 is intended to be recirculated by the aid of conduit means 17, a pump 18, and a supply line 13 leading back into the main body of water 11. A usual filter tank 19 is interposed in the recirculation path. A selectively adjustable valve 30 controls the flow of water in the conduit 17 to the pump 18.

An outlet conduit 31 between the deep end of the pool

10 and the conduit 17 provides for the circulation of water from the lower levels of the pool, at which place additional foreign material may exist. A valve 32, similar to valve 30, is placed in the conduit 31 and is adjustable. It will first be assumed that the valve 32 is completely closed.

The level 16 must be maintained at a definite value as compared with the ledge 15 and the capacity of the pump 18 in order to maintain proper cleaning efficiency for the pool 10.

If the level 16 exceeds a certain amount for a given rate of withdrawal of the overflow water by the pump 18, the level of water in the gutter 14 must rise. The skimming action of the ledge 15 may be impaired by virtue of an equalization of levels on both sides of the ledge.

On the other hand, should the level 16 of the main body of water be less than a certain amount for a given rate of withdrawal, even to the extent of a few thousandths of an inch, improper operation of the pump will result. Thus, the system will operate to inject air into the pump, thereby producing an undesired air lock. The skimming action will then be irregular. Also, the flow of water will be less than can be accommodated by the pump 18, and the system will not be operating at its peak efficiency.

To overcome these conditions, a sump 21 forms a part of a continuous recirculation path of the water. This sump 21 accommodates a relatively small body of water. It may be formed in an appropriate manner adjacent the gutter 14. The sump 21 maintains a charge for the pump 18 and determines a proper level of the surface 16. It is fed by an outlet conduit 22 from the gutter 14, and it feeds the conduit means 17 to the pump 18. The pump 18 withdraws water from the sump at a substantially constant rate for a given setting of the valve 30. Since the sump 21 is fed by the gutter 14, the level 23 of the sump must be constantly maintained below that of the ledge 15 so that proper skimming action results. If the rate of flow of water over the ledge 15 corresponds precisely to the rate of withdrawal of water by the pump 18 from the sump 21 filled with water, the system will be operating at its maximum circulating efficiency.

Since a certain volume of water must inevitably be lost from the pool 10, through evaporation and other causes, the level of the surface 16 of the pool 10 would ordinarily tend to lower with respect to the ledge 15. To overcome this tendency, an external supply line 20 directly supplies water to the sump 21 as needed to maintain it at a certain level 23, below the level 16 of the pool. For this purpose a valve 24 is illustrated that is controlled by a float 25 in the sump 21. Should the level of the surface 16 lower such as to provide an insufficient flow of water into the sump 21, with respect to the rate of withdrawal therefrom, the float 25 will operate to introduce additional water.

By supplying water directly to the sump 21 rather than to the main body of water 11, it is insured that the pump continuously operates with a full charge of fluid. The water admitted to the sump 21 by the external supply eventually finds its way into the main body of water 11, thereby tending to increase the level 16. The external supply thus brings the system to an efficient equilibrium operating condition wherein the flow of water over this ledge is increased to an amount such that the rate of supplying external water into the sump 21 together with the rate of flow of water thereinto from the skimming gutter 14 corresponds to the rate of withdrawal of water from the sump 21 by the pump 18. The level of the surface 16 is then maintained at a height to produce the maximum surface flow of water that can be handled by the pump 18.

The system will automatically accommodate itself such that the flow of water over the ledge 15 corresponds substantially to the capacity of the pump 18. Since the pump 18 always has a supply of water from the sump 21, which consists of water from the ledge 15 and from the external

supply 20, it will discharge water into the pool at a rate dependent only upon its set operating condition. Thus, if the rate of withdrawal of water from the sump 21 by the pump 18 is suddenly increased, such as by further opening the valve 30, the pool 10 momentarily receives more water than is discharged therefrom over the ledge 15. But such condition is soon overcome when the level of the surface 16 rises under the influence of a greater rate of supply of water from the supply outlet 12. At such time, the discharge over the ledge 15 increases by virtue of the increased incremental height of the surface 16. Such increased discharge over the ledge 15, plus the water added to the sump 21 from the external supply 20, will bring the system into equilibrium for a greater rate of circulation.

Should the rate of withdrawal of water from the sump 21 be suddenly reduced, such as by manipulating the valve 30, the pool 10 momentarily will discharge more water over the ledge 15 than it receives from the supply outlet 12. The level 23 of the sump 21 will then rise above the cut-off position of the float 25. The level 16 above the ledge 15 will then drop to a point in which the discharge rate into the gutter 14 is balanced by the rate of supply from the pump 18. Evaporation soon reduces the water in the system, and the level in the sump 21 then drops below the cut-off position of the float 25, and normal steady state operation resumes for a reduced rate of circulation. The level of the sump 21 may normally be sufficiently below the top of the ledge 15 so as to ensure that even in the event of an extreme rise in the level of the sump 21, such as occasioned by a sudden lowering in the rate of withdrawal of water from the sump 21 by the pump 18, the sump water does not rise sufficiently to impair proper skimming action.

By utilizing the sump construction 21 with a float 25 directly responsive to an increased capacity of the pump 18, the system can smoothly adjust itself for operation according to the condition of the pump 18 and the setting of the valve 30.

The present system makes it possible to use a small size pump 18, minimizing the cost of a circulating system, but yet insuring that the level of the surface 16 corresponds precisely to the requirements of the pump 18.

Since the sump 21 is small in volume in comparison with any normal rate of flow of water over the ledge 15, the level 23 of the sump is extrasensitive to such rate of flow. A substantial change in this level 23 will be caused by even a slight change in flow of water over the ledge 15, such as may be caused by a loss in height of the surface 16 of a few thousandths of an inch. Accordingly, the float valve 24 can be of ordinary construction, and yet the float 25 operating the valve will effectively provide the proper volume of water for the system.

If the valve 32 is opened during the operation of the skimming system, precisely the same skimming action results. A portion of the pump capacity is then used for recirculating water from the bottom of the pool 10, and not all of the pump capacity is useful for withdrawing water from the sump 21 and keeping the level of water in the pool 10 above the skimming ledge. The combined setting of the valves 30 and 32 determines the rate of withdrawal of water from the sump 21 for a given operating condition of the pump 18. The combined setting of the valves 30 and 32 determines the skimming rate, rather than the valve 30 alone.

It has been assumed that the external supply line 20 is capable of a sufficient flow rate to prevent a material drop in the level of water in the sump 21 below the cut-off position of the float 25. The supply line 20, however, may not be sufficient to meet high requirements of the pump 18 to maintain a charge for it, especially if the level of the water 11 of the pool 10 is lower than the ledge 15.

For the purpose of insuring that the pump 18 always

has a sufficient charge of water, despite a small supply conduit 20, a plug valve construction 26 is carried by a stem 27 secured to the float 25. The plug 26 has a series of angularly spaced longitudinal grooves 28, permitting only a restricted passage of water into the conduit 17 and to the pump 18 when the plug 26 is positioned at the inlet of the conduit 17. The combined area of the grooves 28 will be sufficiently small such that, when the plug is positioned, the flow to the conduit 18 is restricted to an amount at least equal to or, preferably, less than the maximum rate of supply capable of the conduit 20. Accordingly, the level of water in the sump 21 will be prevented from any further substantial lowering, and the pump 18 will have a sufficient charge of water to prevent it from operating under undesirable conditions.

For guiding the plug 26, a guide 29 dependently carried from the plug 26 is accommodated within the conduit 17. It insures that the plug 26 will cooperate with the conduit 17 upon a drop in level 23. The guide 29 may be of any suitable form. In the present instance, it is in the form of a plurality of radial arms.

At the normal shut-off level 23 indicated in the drawings, the plug 26 is sufficiently above the conduit 17 such that it will not materially influence the rate of flow from the sump 21, such as was first described.

In the form illustrated in Figs. 6 and 7, a slightly different construction is shown for insuring a sufficient charge of water for the pump 18.

In the present case, a conduit 33 is provided in place of conduit 17. This conduit 33 extends upwardly from the bottom of the sump 21. A butterfly valve 34 within the conduit 33 has secured thereto a stem 35 extending through and beyond appropriate apertures 36 of the conduit 33 for pivotally mounting the valve 34.

The plane of the butterfly valve normally extends longitudinally of the conduit 33, but may be adjusted about the axis of the stem 35 to provide a reduced rate of flow from the sump 21 upon a substantial drop in the level 23. For this purpose, a crank arm 37 has one end carried by the stem 35 for rotation therewith. The other end of the crank arm is secured to the float 25 by a chain 38. For mounting the chain to the arm 37, a bolt 39 is provided that is threadedly carried by the arm 37 and about which a link of the chain extends. On the other end of the stem 35, a crank arm 40, similar to crank arm 37, is provided. This crank arm 40 is secured to the stem 35 for rotation therewith. A weight 41 appropriately carried by the arm 40, as illustrated in Fig. 7, is so positioned on the shaft with respect to the chain mounting 39, such as to maintain the chain 38 taut for all positions of the float 25.

If the level 23 in the sump decreases materially, the operating mechanism for the butterfly valve 34 causes the plane of the valve 34 to be transverse to the length

of the conduit 33, thereby reducing the apparent capacity of the pump 18 and insuring a charge for the pump 18.

At a horizontal position of the butterfly valve 34, corresponding to maximum throttling, there is a sufficient passage of water around the periphery of the valve 34 to permit a limited flow of water.

Even with a restricted flow to the pump 18, such as is permitted by the plug 26 or valve 34, the level of the pool 10 will ultimately rise such as to provide a flow of water into the sump 21 from over the skimming ledge. When a sufficient amount of water has been added to the system, the level of water in the sump 23 returns to at least the cut-off level of the float 25, and normal operation as above described is resumed.

15 The inventor claims:

1. In a circulatory system for a body of liquid in a container: a sump for receiving liquid from the container; a pump having an inlet connected to the sump and an outlet adapted to discharge into the container; a float cooperating with the liquid in the sump; a valve operated by the float for controlling an external source of liquid; said valve being operable upon a lowering of the float from a pre-determined level to introduce additional liquid into the sump; and a ported plug cooperating with said inlet and carried by said float for restricting the flow of liquid into said inlet upon a lowering of the level of liquid in the sump in a pre-determined amount.

2. In a circulatory system for a body of liquid in a container: a sump for receiving liquid from the container; 30 a pump having an inlet connected to the sump and an outlet adapted to discharge into the container; a float cooperating with the liquid in the sump; a first valve operated by the float for controlling an external source of liquid; said first valve being operable upon a lowering of the float from a pre-determined level to introduce additional liquid into the sump; and a second valve cooperable with said inlet, said second valve approaching closed position upon a lowering of the level of liquid in said sump.
